CLAIM

The ornamental design for a catheter assembly with needle, guide wire and catheter, as shown and described.

DESCRIPTION

FIG. 1 is a top perspective view of a catheter assembly with needle, guide wire and catheter showing my new design in a first configuration.

FIG. 2 is a right side elevational view thereof.

FIG. 3 is a left side elevational view thereof.

FIG. 4 is top plan view thereof.

FIG. 5 is bottom plan view thereof.

FIG. 6 is front elevational view thereof.

FIG. 7 is a rear elevational view thereof; and,

FIG. 8 is a top perspective view thereof in a second configuration.

The broken line showing of portions of the catheter assembly with needle, guide wire and catheter form no part of the claimed design.

The dot-dash-dot line shown in the drawings defines a boundary line for the claimed design.
